UNITED STATES PATENT OFFICE.

JOHN H. JENNER, OF LEAVENWORTH, INDIANA.

WRENCH.

SPECIFICATION forming part of Letters Patent No. 576,454, dated February 2, 1897.

Application filed November 6, 1896. Serial No. 611,256. (No model.)

To all whom it may concern.

Be it known that I, JOHN H. JENNER, of Leavenworth, in the county of Crawford and State of Indiana, have invented a new and Improved Wrench, of which the following is a full, clear, and exact description.

The object of the invention is to provide a new and improved wrench of the "alligator" type, and which is simple and durable in construction and readily adjustable for engaging and properly gripping pipes, rods, &c., of different diameters.

The invention consists principally of a removable jaw and a slideable jaw having its gripping-face at angles to the stock member on which the jaw is fitted to slide.

The invention also consists of certain parts and details and combinations of the same, as will be fully described hereinafter and then 20 pointed out in the claims.

Reference is to be had to the accompanying drawings, forming a part of this specification, in which similar characters of reference indicate corresponding parts in all the figures.

25 Figure 1 is a side elevation of the improvement. Fig. 2 is a plan view of the same. Fig. 3 is a sectional side elevation of the same on the line 3-3 of Fig. 2, and Fig. 4 is an enlarged end elevation of the slideable jaw.

30 The improved wrench is provided with a stock A, having a handle A', and forked members A² and A³, extending at angles to each other, as is plainly indicated in Figs. 1 and 3. On the member A² is held a removable 35 jaw B, and on the member A³ is arranged a slideable jaw C, the gripping-face C' of which stands at an angle to the top of the member A³. Thus when the article is gripped by the jaws B and C and the stock is moved to turn 40 the article then the pressure on the inclined face C' of the jaw C securely holds the latter in position on the member A³.

The removable jaw B is formed at its inner face with teeth or serrations B', and the inner end of the said jaw is formed with a circular offset B², fitting into a correspondingly-shaped recess A⁴, formed in the stock A at the apex of the members A² and A³. The outer end of the jaw B is formed with an upwardly-extending lug B³, engaging a recess A⁵, formed in the free end of the member A², the said lug B³ being fastened in place by a

pin D, driven transversely in the member A² and through an opening in the lug B³. Now by removing the pin D the jaw B can be 55 swung inward, with the offset B² as the fulcrum, until the lug B³ is out of engagement with the member A², and then by moving the jaw B transversely the latter can be readily disengaged from the stock A. Thus whenever the jaw B is worn out it can be readily removed and replaced by a new one.

The jaw C is preferably made in the shape of a casing fitted to slide on the member A³, and is prevented from dropping off the said 65 member by a pin E, attached to the said member and projecting from the sides thereof to engage the sides of the jaw C. By removing the pin E the jaw C is slipped off the member A³ and replaced by a new one whenever necessary.

Now it will be seen that by the arrangement described the movable jaw C can be 70 readily slipped or shifted along the member A³, according to the size of the article to be gripped, to make the wrench useful for gripping pipes, rods, and the like of different diameters.

By having the toothed or serrated face C' of the movable jaw C at an angle to the top 80 of the member A³ the jaw is not liable to slip on the said member when the wrench is used for turning the article gripped between the jaws. The jaws may be made of steel or other suitable material, and as they are removable and separate from the stock of the wrench they can be properly tempered and hardened.

The jaws may be made of rubber or other elastic material for gripping polished surfaces 90 without marring the same.

Having thus fully described my invention, I claim as new and desire to secure by Letters Patent—

1. A wrench, comprising a stock formed 95 with forked members, a jaw removably held on one of the said members, and a second jaw in the form of a casing loosely mounted to slide upon the other member and having its gripping-face inclined toward the inner end 100 thereof, substantially as shown and described.

2. A wrench, comprising the stock formed with forked members, a jaw formed at its in-

ner end with an offset arranged to fit in a correspondingly-shaped recess in the stock at the apices of the forked members and at its outer end with a lug received in a recess in one of said members, a pin inserted through apertures in the aforesaid member and in said lug, and a second jaw in the form of a casing mounted to slide on the other member of the

stock which is provided at its forward end with a pin arranged to limit the outward movement of the said jaw, as and for the purpose described.

JOHN H. JENNER.
